UNITED STATES PATENT OFFICE.

HENRY A. WISE WOOD, OF NEW YORK, N. Y., ASSIGNOR, BY MESNE ASSIGNMENTS, TO DETROIT TRUST CO., TRUSTEE, OF DETROIT, MICHIGAN.

PRINTING-MACHINE.

SPECIFICATION forming part of Letters Patent No. 735,646, dated August 4, 1903.

Application filed May 14, 1894. Renewed January 12, 1903. Serial No. 138,662. (No model.)

To all whom it may concern:

Be it known that I, HENRY A. WISE WOOD, a citizen of the United States, residing at New York, in the county of New York and State 5 of New York, have invented a new and useful Improvement in Printing-Machines, of which the following is a specification.

This invention relates to that class of printing-presses which are known as "traveling-cylinder" web-printing presses; and the objects of my invention are to provide a compact, durable, and convenient construction which will occupy very little floor-space and a press which may be operated at a high speed 15 which will require comparatively little power.

To these ends my invention consists of the parts and combinations of parts as herein-after described, and more particularly pointed out in the claims at the end of this specification. 20

In the accompanying two sheets of drawings, Figure 1 is a side elevation of a printing-press constructed according to my invention, and Fig. 2 is a diagrammatic sectional view 25 of the same.

Referring to the drawings and in detail, A represents a locomotive or traveling impression-cylinder which is journaled in a suitable carriage or carriages E, fitted on ways on the 30 main frame, which impression-cylinder is adapted to coöperate with a stationary form-bed C. Journaled or mounted in the carriage E in any approved manner, at each side of the impression-cylinder A, I provide form-rollers F, which coöperate with ink-tables T and with distributing-rollers J, which latter may be supplied with ink from ink-fountains K of any of the usual or preferred constructions by any suitable means, as ductor-rolls, 35 as shown. If desired, springs may be used to keep the form-rollers in place in the carriage.

B designates the second impression-cylinder, which is journaled in a suitable carriage E', mounted on guides on the frame, as shown, and which impression-cylinder coöperates with a stationary form-bed D. Journaled or mounted in the carriage E' are form-inking rollers F', which coöperate with ink-table T', 40 and distributing-rollers J', to which ink is supplied from the fountains K', as described

in connection with the first impression-cylinder.

The stationary form-beds C and D face outwardly and are secured to side frames 10 on 55 the press. The essential feature of this arrangement is that the beds should be arranged substantially back to back and face outwardly, no matter whether they are relatively inclined or not.

My invention consists, in the first place, in the new manner in which the web is led through a press of this general description. The web w is unwound from the web-roll W and is then led up, over, and around the constantly-running feeding-in roll 11, with which coöperate the endless tapes 12, which pass over the tape-pulleys 13, 14, and 15, which tape-pulleys may be driven by suitable gearing. From the feeding-in roll 11 the web 60 passes down under the looping-in roller 16, up around the guide-roller 17, over and around the guide-roller 18, carried by the cylinder-carriage E, down, under, and around the first impression-cylinder A, over the roller 19, also 65 carried by the cylinder-carriage E, over and around guide-rollers 20 and 21, down between the two stationary form-beds C and D, under and around the guide-roller 22, under and around the roller 23, which may be made 70 adjustable in any of the approved ways, up around the guide-roller 24, over and around the guide-roller 25, carried by the cylinder-carriage E', down, under, and around the second impression-cylinder B, over the guide 75 26, also carried by the carriage E', around the guide-roller 27, up, over, and around the looping-out roller 28, down, over, and around the constantly-running feeding-out roller 29, with which coöperate the feeding-out tapes 80 30, which pass over tape-pulleys 30, 32, and 33, which may be driven by any suitable gearing, (not necessary here to show.) From the constantly-running feeding-out roller 29 the web 85 may be led to any preferred form of cutting and folding or delivery mechanism. By this passage of the web through the press it will be seen that a very direct and short path for the web is provided and one that contains very few corners and also one through which 90 the web can be quickly threaded; also, it will be seen that the web passes from the first

looper to the first press over a very slight corner and from the second press to the looping-out roller over a very slight corner. This enables the loopers to put almost a direct pull upon the web; also, as hereinafter described, it will be seen that as the impression-cylinders preferably are reciprocated in opposite direction that the strain or trend of the web from each impression-cylinder will counter-balance each other, whereby the press can be run at a very high rate of speed. Of course the same advantages would be obtained and it would be within the scope of my invention to run the web through the press in the opposite direction—that is, to lead the web in over the looping-roller 28 and out over the looping-roller 16.

The gearing for driving the press which I may employ is substantially inclosed by the stationary form-beds C and D and the side frames 10 and may be arranged as follows: 320 designates the power-shaft, to which power may be applied in any of the ordinary or preferred manners. Fastened to the power-shaft 320 is a pinion 330, which meshes with an intermediate 33, which intermediate 33 drives a gear 34, fastened on the driving-shaft 35. Secured on the inner end of the driving-shaft 35 is a crank-disk 36, which carries a crank-pin 37, which connects by pitman 38 to a sector 39, pivoted on a transverse stud or shaft 40. Meshing with and engaging the sector 39 is a gear 41, mounted on a shaft 42, journaled in the side frames, and this shaft 42 carries gears 43, preferably on the outside of each frame, as shown. The gears 43 mesh with and drive gears 44 and 45, which in turn mesh with and engage racks 46 and 47, carried by the cylinder-carriages E and E', and I preferably use gears 44 and 45 on each side of the press, so that the mechanism will square. By this means it will be seen that I have provided a strong and efficient driving mechanism which is adapted to move the impression-cylinders preferably in opposite directions and one which has its vibrating parts housed within the framing. By this means the impression-cylinders will counterbalance each other and can be run at a high rate of speed.

In some instances I contemplate arranging the gears 43, 44, and 45 and the rack-bars just inside of the frames, the gears 44 and 45 being set up through stationary beds, so that the entire gearing will be out of the way.

The gearing for driving the web-feeding devices may be arranged in any convenient manner, and, as shown in the drawings, 50 designates a gear which meshes with and engages the intermediate 33. Secured to the gear 50 I provide a suitable heart-shaped cam 52, which engages and actuates a roller mounted on a bell-crank lever 53. The shaft on which the bell-crank lever 53 is mounted is preferably carried across the press, and a similar lever 53 is arranged on the other side of the press. Springs 530 are arranged, as shown, in connec-

tion with these bell-crank levers, so as to keep the roller against the cam. The bell-crank levers at one end are connected with and actuate the looping-in roller by means of pitmen 54, as shown. The opposite arms of the bell-crank levers 53 are connected by pitmen 55 with bell-crank levers 56, which are connected by pitmen 57 with the pivoted levers 58, which are connected to and actuate the looping-out roller by means of pitmen 59, as shown.

The cam, gearing, and connections before described are so proportioned that the cam will make two turns for each forward and backward movement or complete cycle of the impression-cylinders, so that the web will be fed while the impression-cylinders are off impression in either direction, whereby two perfected sheets will be printed at each cycle.

The gearing for driving the feeding-in and feeding-out rollers may be arranged as follows: As shown, 60 designates a change-gear, which is journaled on a stud in the sweep 61 and which change-gear 60 meshes with the gear 34. The gear 60 has on the other side of the sweep a gear 600, which by setting the sweep may be made to mesh with a gear 62, secured to or upon the same shaft with a bevel-gear 63, the bevel-gear 63 driving the horizontal shaft 65 by means of the bevel-pinion 64, as shown. The horizontal shaft 65 is geared at one end by the bevel-gears 66 and 67 to actuate and drive the feeding-in roll 11. At its other end the shaft 65 is geared to a vertical shaft 70 by means of the bevel-gears 68 and 69, and the shaft 70 is geared with and drives the feeding-out roller 29 by means of the bevel-gears 71 and 72.

By changing the gear 60 and the cam 52 various lengths of sheets within the limits of the press may be printed and delivered.

It will thus be seen that I have provided a strong, simple, and compact printing-machine with a very simple and direct-driving mechanism, which may be actuated with comparatively little power, as the parts are arranged to substantially counterbalance each other, and one in which the trends on the web from the two impression-cylinders will offset each other. Also it will be seen that I have provided a very direct path of travel for the web, which is fed into the machine at one side and fed out of the machine at the opposite side in such a position that it can be readily carried to any folding or delivering mechanism.

I am aware that many changes in the design of the gearing and arrangement of the various operating parts can be made by those who are skilled in the art, and I do not, therefore, wish to be limited to the details which I have shown and described; but

What I do claim, and desire to secure by Letters Patent of the United States, is—

1. In a printing-machine, the combination of two inclined, stationary form-beds, traveling impression-cylinders co-operating therewith, guides for the web for leading a web of

paper over one of said form-beds, between said form-beds, and over the second form-bed, whereby the web may be printed and perfected by said traveling impression-cylinders.

2. The combination of two stationary, oppositely-inclined form-beds facing outwardly, a traveling impression-cylinder coöperating with each form-bed, and guides for leading a web of paper up over the first form-bed, down transversely between said form-beds, and up over the second form-bed, whereby the web is printed and perfected by the traveling impression-cylinders.

3. In a printing-machine, the combination of two stationary form-beds arranged back to back, a traveling impression-cylinder coacting with each of said form-beds, guides for leading a web of paper over one of said form-beds, between said form-beds, and over the second form-bed, whereby the web may be printed and perfected by said traveling impression-cylinders, and suitable web-manipulating mechanism.

4. In a printing-machine, the combination of stationary form-beds, traveling impression-cylinders coacting therewith, a transverse shaft having driving-gears secured near its ends, means for rotating the shaft alternately in opposite directions, pinions driven by the gears on the transverse shaft and serving to actuate the impression-cylinders alternately in opposite directions.

5. The combination in a web-printing machine, of two stationary form-beds arranged back to back, a carriage mounted so as to be capable of moving parallel with each bed, an impression-cylinder journaled in each of said carriages, web-guides, a web-manipulating mechanism, and a positively-actuating driving mechanism for reciprocating said carriages arranged below and between said beds.

6. The combination in a web-printing machine, of two stationary form-beds arranged back to back, a carriage mounted so as to be capable of movement parallel with each bed, an impression-cylinder journaled in each of said carriages, web-guides arranged to direct the web over one bed, between the beds, and then over the other bed, a web-manipulating mechanism, and a positively-actuating driving mechanism for reciprocating said carriages arranged below and between said beds.

7. In a printing-machine, the combination of stationary form-beds, traveling impression-

cylinders coacting therewith, a driving mechanism for said impression-cylinders, comprising a crank-shaft to which power may be applied in any ordinary or preferred manner, a sector actuated by said crank-shaft, a transverse shaft actuated by said sector, and gearing for connecting said transverse shaft with the impression-cylinders.

8. In a printing-machine, the combination of two inclined, stationary form-beds facing outwardly, a traveling impression-cylinder coacting with each of said form-beds, and a driving mechanism for moving said impression-cylinders alternately in opposite directions, comprising a crank-shaft, to which power may be applied in any ordinary or preferred manner, a sector actuated by said crank-shaft, a central transverse shaft driven in opposite directions by said sector, gears carried by said transverse shaft, which are geared to actuate the cylinder-carriages alternately in opposite directions.

9. In a printing-machine, the combination with two stationary inclined form-beds facing outwardly, a traveling impression-cylinder coacting with each of said form-beds, and journaled in a suitable carriage, rack-bars carried by each of said carriages, and gearing for driving said impression-cylinders, comprising a crank-shaft, a sector actuated by said crank-shaft, a transverse shaft actuated in opposite directions by said sector, and gearing between said transverse shaft and the rack-bars carried by the carriages, for moving the cylinder-carriages alternately in opposite directions.

10. In a printing-machine, the combination with two stationary inclined form-beds, a traveling impression-cylinder coacting with each of said form-beds, suitable web-guiding mechanism, means for feeding the web into and out of the press, and a vertically-moving feeding-in looper, and a vertically-moving feeding-out looper, arranged to operate on the web, at a slight angle to the path of the web over the form-beds.

In testimony whereof I have hereunto set my hand in the presence of two subscribing witnesses.

H. A. WISE WOOD.
